Sault Sainte Marie, Mich.

Application May 29, 1945, Serial No. 596,454

4 Claims. (Cl. 60—41)

1

This invention relates to turbines, and more particularly, to internal combustion gasoline turbines.

A main object of the invention is to provide a novel and improved gasoline turbine wherein the fuel mixture is compressed prior to admission into the firing chamber and fed under pressure into the firing chamber where it strikes the rotary blades causing steady rotation and fire overlap.

A further object of the invention is to provide an improved gasoline turbine utilizing pre-compression of the fuel mixture, and wherein improved regulating means for controlling the pressure of the compressed fuel mixture is employed.

Other objects and advantages of the invention will appear from the following description and claims, and from the accompanying drawings, wherein:

Figure 1 is a longitudinal cross-sectional view taken on line 1—1 of Figure 2 of an embodiment of a gasoline turbine in accordance with this invention.

Figure 2 is a vertical cross-sectional view taken on line 2—2 of Figure 1.

Figure 3 is a detail cross-sectional view of an exhaust pipe fitting taken on line 3—3 of Figure 2.

Figure 4 is a detail view of the valve structure employed in the air compression cylinder of the gasoline turbine of Figure 1.

Referring to the drawings, 6 designates a motor shaft which is adapted to be driven by a turbine wheel 2 contained within a housing 4, said shaft 6 being rotatively supported with respect to housing 4 by a pair of bearings 3, 3, the outside bearing being provided with a protecting cover plate 5.

Formed in housing 4 are a plurality of firing chambers 1, each chamber being provided with an intake slide valve 7 and a spark plug 25 for exploding the fuel mixture furnished to chamber 1. Appropriately peripherally spaced with respect to each firing chamber is an exhaust port 48 and an exhaust pipe for exhausting the exploded mixture after delivery of its power stroke to the blades of the turbine wheel 2, the exhaust pipes being connected to a conventional exhaust manifold.

The timing of valve 7 is controlled by an appropriate cam 49 which is mounted on shaft 6, said cam 49 actuating slide valve 7 by contact with a follower member carried by said slide valve.

The timing of the spark at each spark plug 25 is controlled in a conventional manner by the

2

setting of a distributor point 23 of a distributor 22 driven from shaft 6, distributor point 23 being connected to spark plug 25 by a cable 24.

The cooling system comprises a fan 10 mounted on the shaft of a generator 11, fan 10 being connected by an air duct 9 to a peripheral air chamber 8 provided in the turbine housing 4. Generator 11 carries on its shaft a gear 12 which meshes with an oil pump gear 13 which in turn 10 meshes with a gear 14 carried on shaft 6. The gear train thus drives generator 11 and fan 10.

Provided adjacent housing 4 is a housing 50 through which shaft 6 passes. Journaled in housing 50 is a crankshaft 17 carrying a gear 15 15 adapted to be connected thereto for rotation of the crankshaft by a clutch 16. Gear 15 meshes with gear 14. Crankshaft 17 is provided with a crank provided with a connecting rod 18 which is pivotally connected to a piston rod 51 passing 20 through a packing nut 20 into a cylinder 52, said piston rod being provided with a piston 19. A plate 53 is provided, forming the lower wall of cylinder 52. An air intake valve 42 is provided in said plate 53, said intake valve being connected to the atmosphere by a conduit 54. An air outlet valve 41 is provided in plate 53, said outlet valve being connected by a conduit 31 to an intake valve 55 provided in a compression tank 37. The reciprocation of piston 19 in cylinder 52 will thus be effective to pump air into tank 37.

Crankshaft 17 is provided with a first cam 38 which reciprocates a slide valve 40, and a second cam 39 which reciprocates a poppet valve 27. A fuel tank 45 furnishes fuel through a conduit 46 to a carburetor 30 from which the fuel is delivered through slide valve 40 to a chamber 56 above piston 19. The fuel is pumped by piston 19 into a compression head 28 from which it is delivered 10 to tank 37. The cams 38 and 39 are arranged with respect to the crank or crankshaft 17 so that valve 27 opens and valve 40 closes while piston 19 is delivering its power stroke, while said valve 40 is opened and valve 27 is closed during 15 the return stroke of piston 19. Sufficient suction is developed on the return stroke of piston 19 to draw a substantial charge of fuel into chamber 56.

The fuel is pumped from compression head 28 20 to compression tank 37 either through a priming conduit 57 and a first spring-biased priming valve 35, or through a main fuel conduit 29 and a second spring-biased main valve 58 to an intake valve 59. Valve 35 is arranged to admit fuel 25 into tank 37 until a normal working pressure is

developed therein, for example, 35 pounds per square inch, whereupon valve 35 is closed. Valve 58 comprises a cylinder containing a sleeve 33 slidably positioned in an outlet port 60, the upper end of sleeve 33 being normally in abutment with a seat provided at the top of said cylinder to close off said sleeve. A biasing spring 32, positioned between a piston element 61 rigidly secured to sleeve 33 and a washer element 62 supported in the lower portion of said cylinder provides the normal biasing thrust which closes off the top end of sleeve 33 until a substantial pressure is developed in conduit 29. Valve 58 thus acts as a relief valve to close off the main fuel conduit 29 until adequate fuel compression is obtained in compression head 28.

An outlet port 63 is provided in tank 37, provided with a throttle 64 through which the fuel mixture passes into a conduit 26 and from thence through valve 7 into firing chamber 1. Throttle 64 is normally controlled by a lever 44 provided with a locking dog 47 cooperating with a conventional rack segment to hold the throttle in a desired position of adjustment.

A spring-biased piston member 36 is provided in a cylindrical recess formed in tank 37, said piston being connected to a lever 34 which in turn is connected to a control linkage for clutch 16. When the pressure in tank 37 rises above a desired limiting value, piston 36 is urged rearwardly against its spring, causing lever 34 to rotate and to disengage clutch 16 until the pressure in tank 37 has decreased to a safe value.

When the turbine is started, it is rotated by an appropriate starting motor and fuel is pumped under low pressure from carburetor 30 into compression chamber 28 and thence through priming conduit 57 and past priming valve 35 into tank 37. Since the amount of air pumped into compression chamber 37 by piston 19 at this time is small, a relatively rich mixture is fed past throttle 64 into the firing chamber. This condition continues until the turbine comes up to normal operation and a substantial pressure is developed in compression tank 37. Valve 58 then opens and valve 35 is closed, the turbine then being operated at the optimum mixture ratio of air and fuel, the operating pressure of tank 37 being held to a safe value by the pressure-responsive clutch-disengaging piston member 36.

The moving parts within housing 50 are lubricated by an oil pump 66 actuated by gear 13, an appropriate oil reservoir 21 being provided in the lower portion of housing 50 and a force feed oil duct 65 being provided for said oil pump.

An appropriate base 43 for the turbine housing is provided, said base being adapted to be secured to conventional supporting means.

By adjustment of throttle 64 the speed of ro- 60

tation of the turbine wheel may be varied over a substantial range.

While a specific embodiment of an internal combustion turbine structure has been disclosed in the foregoing description, it will be understood that numerous modifications within the spirit of the invention may occur to those skilled in the art. Therefore, it is intended that no limitations be placed on the invention other than as defined by the scope of the appended claims.

What is claimed is:

1. A turbine comprising a housing, a turbine wheel rotatably mounted within said housing, a fluid nozzle positioned adjacent the periphery of said wheel, a firing chamber in said housing communicating with said nozzle, a compression tank, means actuated by said wheel for forcing air and combustible liquid fuel into said compression tank, and conduit means for admitting the mixture of air and fuel into said firing chamber, said means for forcing air and fuel into said compression tank having a clutch means in association therewith adapted to disengage said wheel from said forcing means responsive to an increase in pressure in said compression tank above a predetermined value.

2. A turbine comprising a housing, a turbine wheel rotatively mounted within said housing, a fluid nozzle positioned adjacent the periphery of said wheel, a firing chamber in said housing communicating with said nozzle, a compression tank, means actuated by said wheel for forcing air and combustible liquid fuel into said compression tank, conduit means for admitting the mixture of air and fuel into said firing chamber, the forcing means comprising a pump geared to said wheel having an air pumping section adapted to force atmospheric air into said compression tank and a fuel pumping section, said fuel pumping section communicating with said compression tank by a first fuel feed conduit having positioned therein a valve adapted to open only against low pressure in said compression tank and by a second fuel feed conduit having positioned therein a valve adapted to open only by a normal difference in pressure between the pressure of the fuel pumping section and the pressure in the compression tank.

3. The structure of claim 2, and wherein pressure-responsive means is provided in said compression tank adapted to disengage said pump from said wheel responsive to an increase in pressure in said compression tank above a predetermined value.

4. The structure of claim 2, and wherein a manually adjustable throttle is provided in said conduit means.
